HANDCUFF

Frida Victoria Forsell, Stockholm, Sweden

Application May 24, 1943, Serial No. 488,220
In Sweden April 15, 1942

3 Claims. (Cl. 70—17)

The present invention relates to handcuffs and is more particularly concerned with that type of handcuffs which comprises a handle carrying a movable and spring-actuated claw which is adapted to be held in its opened position by a locking mechanism which is actuated by a trigger mounted on the handle. The main object of the invention is to provide a trigger mechanism which prevents inadvertent opening of the handcuff. Other objects will be evident from the following description.

A preferred embodiment of the handcuff according to this invention is illustrated in the accompanying drawing in which:

Fig. 1 is a side view of the handcuff with a cover piece removed;

Fig. 2 is a view similar to that of Fig. 1 but with the mechanism in another position; and

Fig. 3 is a plan view of the device with the parts in the same position as in Fig. 2.

The handle or grip 1 of the handcuff is provided with a casing 2 containing a locking mechanism and having fixedly connected to it one claw 3 of a handcuff, the other, or movable, claw 4 of which is provided with a disc-like hub portion 5 by means of which it is pivoted on a pin 6 in the casing 2. The movable claw 4 is actuated by a spiral spring 7 which tends to move this claw towards the fixed claw 3. The disc-like hub portion 5 is provided with two recesses 8 and 9 in its periphery into which a hook 10 at one end of a two-armed lever 11 may enter in order to lock the movable claw in either the opened or the closed position. The lever, or latch, 11 is pivoted on a pin 12 in the casing 2 and is actuated by a spring 13 which tends to turn the latch to the left so that the hook 10 is kept in contact with the periphery of the hub portion 5. The other end of the latch 11 is adapted to coact with one end of a bar 14 which is mounted in a groove 15 provided in the handle 1, said groove being of such dimensions that the bar may be displaced longitudinally and also tilted to a certain extent therein. A spring 16 arranged within the casing 2 is adapted to actuate the bar 14 to keep the same in contact with the bottom of the groove 15. The other end of the bar 14 engages a recess between two projections 17 and 18 at one end of a trigger 19 which is displaceable in a groove in the handle 1 and connected to the handle by means of a screw 20 which passes loosely through an elongated slot 21 in the trigger. The arrangement is such that the trigger 19 may be depressed after it has been

displaced longitudinally enough to move the projection 18 clear of a stop surface 22 in the handle 1. At the depression of the trigger the latch 11 is swung to the right against the action of the spring 13 from the position shown in Fig. 1 to the position in which the hook 10 does not engage the recess in the hub portion, and the movable claw 4 may be turned to the position shown in Fig. 2. When the trigger is released the spring 13 turns the latch 11 back so that the hook 10 enters into the recess 9 and locks the movable claw in its opened position. Simultaneously the bar 14 and the trigger 19 are moved back to their initial positions by the springs 15 and 16 in which position the surface 22 prevents the trigger from being depressed unless it is also displaced in a direction at about right angles to that of the depression. This construction prevents inadvertent opening of the handcuff by the police officer or by the prisoner.

What I claim and desire to secure by Letters Patent is:

1. In a handcuff, a handle, a movable claw mounted on said handle and capable of being moved to opened and closed position, means for locking said claw in either of said positions, a spring adapted to actuate the claw for moving the same to closed position, and a trigger mounted on the handle and adapted to actuate the locking means, said trigger being mounted for movement first in one direction and then in a direction at about right angles to the first-mentioned direction.

2. In a handcuff, a handle, a claw movably mounted on said handle and capable of being moved to opened and closed position, a spring adapted to actuate said claw for moving the same to closed position, a hub portion on said claw, said hub portion being provided with a pair of recesses, a latch, a spring adapted to move said latch towards said hub portion and into engagement with either of said recesses, a bar for actuating said latch, and a trigger for actuating said bar, said trigger being mounted for two-fold movement.

3. A handcuff according to claim 2, wherein the bar and the trigger are slidably mounted in grooves in the handle and wherein a stop is provided for the trigger which prevents depression thereof and hence actuation of the bar and the associated latch until the trigger has been moved clear of said stop.
